No 1,039.

Design for Plates of a Parlor Stove,
by N. S. Yedder, of Troy, N.Y.

Patented Aug. 10. 1858.

Des. 1039

N. G. Wedder, of Troy, N. Y.
Letters Patent No. 1039 - dated Aug. 10, 1858.

The schedule referred to in these Letters Patent and making part of the same.

To all whom it may concern:

Be it known that I, N. G. Wedder, of the City of Troy, in the County of Rensselaer, and State of New York, have invented or produced a new and original Ornamental Design for Plates of a Parlor Stove; and I do hereby declare that the following is a full and exact description of the same, reference being had to the annexed photographs making a part of this specification, in which Fig. 1. is the front or back plate and Fig. 2. the hearth plate. -

My ornamental design for parlor stove plates consists of the shell a, support b, arches scroll-moldings c, arched moldings d, bases e, and pendants f, all formed and arranged upon the front or back-plate as represented in Fig. 1. and the radiating channels g, and border molding h, formed in and upon the hearth plate as shown in Fig. 2.

What I claim as my invention or production and desire to secure by Letters Patent is the ornamental design, herein described and represented in the annexed photographic drawings, for parlor stove plates.

Witnessed by
John Moran. A. T. Park. N. G. Wedder.
